UNITED STATES PATENT OFFICE

ARTHUR A. JOHNSON, OF BRIDGEPORT, CONNECTICUT, ASSIGNOR TO AUTOGRAPHIC REGISTER COMPANY, OF HOBOKEN, NEW JERSEY, A CORPORATION OF NEW JERSEY

MANIFOLDING REGISTER

Application filed December 24, 1929. Serial No. 416,260.

This invention relates to manifolding machines which, as now provided, may be divided into two general kinds, considering the feed mechanism employed.

In one kind, the feed mechanism is designed to feed the strips which are written upon the machine predetermined and fixed lengths at each operation of the feeding mechanism until the latter is arrested by a stop usually in the path of the handle and rendered inoperative by a manual operation of some kind before the feeding mechanism may be operated.

In another kind, the feeding of the strip is regulated through the medium of apertures in the strips at form-length intervals, the feeding mechanism comprising means which upon engaging the apertures in the strips, renders the feeding mechanism inoperative to continue the advancement until another operation is performed by the operator to again render the feeding mechanism operative upon the strips. The latter kind comprises two types, in one of which a stop which must be released preparatorily to the next feeding operation, is provided to prevent such movement of the feeding mechanism as would cause the feeding operation to be resumed until it is again desired to operate the feeding mechanism. In the other type of this kind, no stop is provided, and the handle may be continuously operated indefinitely without causing the feeding to be resumed after the apertures in the strips have been entered and until a manual operation of the starting device is performed.

An object of the present invention is to avoid the necessity or need for the starting operation being performed by the operator preparatorily to the next feeding operation, and in its broader aspects, has application to the two kinds of manifolding machines above referred to and the two types embraced in the last-referred to kind.

This is accomplished by providing means

for automatically removing the stop which limits the extent of movement of the feeding means in the first kind of manifolding machine referred to and the first type in the second kind, and in automatically operating the starter in the second type of the second kind referred to—namely, the kind of manifolding register disclosed in the Shoup & Oliver Patent #1,396,070.

In connection with the latter, in the broader aspects of the present invention, the starter mechanism may be automatically made operative either upon cessation of movement of the feeding mechanism or upon resumption of the operation of the feeding mechanism when it is desired to again feed-out another form or predetermined length of the strip.

The saving of the extra operation of manipulating the starter or releasing the stop for the handle is extremely advantageous and important, for it enables the written form to be quickly issued from the machine and handed to the waiting customer and permits the operator to give his full attention to the transaction involved.

Other features and advantages will hereinafter appear.

In the accompanying drawings which show several embodiments of the present invention—

Figure 1 is a side view in section and in elevation respectively of the two ends of a register embodying the feed mechanism of the type disclosed in the Shoup & Oliver Patent #1,396,070, showing the parts in the positions they occupy at the completion of the operation of the feeding means and just before the starter is automatically tripped.

Fig. 2 is a top view partly in section of the delivery end of the register, showing the device of the present invention as applied thereto.

Fig. 3 is a side view, showing the parts of the present invention and the parts with

which they operate in the positions occupied during the operation of the feeding means.

Fig. 4 is a similar view, showing the parts in the positions they occupy after cessation 5 of movement of the feeding mechanism, the starter pawl being tripped to permit the feeding operation to be resumed immediately upon the next operation of the feed mechanism.

10 Fig. 5 is a perspective view of the parts provided by the present invention.

Fig. 6 is a modification of the structure of the present invention shown in Figs. 1 to 5 which is adapted to cause the starting device 15 to be tripped at the beginning of the next feeding operation.

Fig. 7 shows the present invention applied to a register having a stop for limiting the movement of the handle or other portion of 20 the feeding mechanism, the top being made inoperative following a predetermined time after cessation of movement of the feeding mechanism.

Fig. 8 is a detail view showing a form of 25 intake valve which may be used on the air pump.

The specific form of this invention elected to be claimed and prosecuted in this application along the generic claims to the invention 30 will first be described, reference being had to Figs. 1 to 5, inclusive.

The invention is shown as applied to a manifolding register having side walls 10, a platen 11, and a marginal frame 12 for supporting and holding in writing position a plurality of fabric strips 13 which are led by suitable guide means 14 from a supply compartment 15 to the platen 11.

The strips 13 are fed over the platen 11 and 40 under the marginal frame 12 by feeding means comprising a pair of annuli or disks 16 carried by a feed shaft 17 and also a pressure roller 18 carried by a frame 19 and pressing the strips 13 into firm contact with the disk 16 by a spring 20. The strips 13 have feed-arresting apertures 21 therein at form-length intervals and aligned with the disks 16 so that when the strips have been advanced to bring a tear-off line 22 beneath a tear-off 50 knife 23 (forming part of a head 24 covering the pressure roller 18), the disks 16 are located in the apertures; and, there being no feeding contact between the disks and the strips, the strips cease advancing while the 55 feed shaft 17 may be continuously operated indefinitely without causing further advancement of the strips.

In order that the strips may be re-engaged by the feeding mechanism, the feed shaft 17 60 is provided with a starting roller 25 located at an unperforated portion of the strips and having a pair of cut-away portions or notches 26, one of which is normally located opposite the pressure roller 18. The starting roller 25 65 is mounted on the shaft so that it need not

rotate with the shaft but tends to turn therewith by reason of a slip clutch connection between it and the shaft and including a disk 27 fixed on the shaft 17 and a disk 28 loose on the shaft and pressed against the starter roller 25 by a spring 29 interposed between the disk 28 and one of the feeding disks 16.

During the feeding operation, the starter roller 25 is held in the position shown in Fig. 1 by a pawl 30 loosely carried on a shaft 31 and engaging a shoulder 32 at one end of the cut-out 26 which is at the side of the roller 25 opposite the cut-out which is then adjacent the pressure roller 18. The pawl is held in this position by a spring 33 which is also anchored in an ear on a tripping lever 34 carried by the shaft 31 and having a laterally extending ear 35 overlying the pawl 30. When the shaft 31 is rocked, the ear 35 engages the pawl and moves its end away from the shoulder 32 on the starting roller and this permits the pawl to jump ahead of the shoulder under the influence of the spring until it engages a shaft 36 extending across the machine. That is to say, the pawl 30 moves to the position shown in Fig. 4, where it is held from again returning to the shoulder 32 by direct engagement with the periphery of the roller 25.

Subsequent rotation of the shaft 17 will cause the starting roller to be rotated and after engaging the strips advance them at least until the apertures 21 in the strips have passed out of range of the feeding disks 16. After this, the starting roller may continue to operate until it makes one half a revolution at which time the pawl 30 is caused by its spring 33 to jump into the depression 26 and engage the shoulder 32 to stop further rotation of the starter roller 25, the remaining portion of the feeding operation being completed solely by the feeding disks 16 and pressure roller 18 until the next set of apertures in the strips are entered by the feeding disks 16.

It will be observed that the feeding mechanism thus far described is substantially the same as that shown in the Shoup & Oliver Patent #1,396,070, and like it the device illustrated has a crank 37 by means of which the shaft 17 may be rotated.

In said patent, and variations and modifications thereof since made, means have always been provided to be operated by the operator to operate the starter shaft 31 by a manual operation so as to render the pawl 30 inoperative preparatorily to the feeding out of a set of forms, except in those embodiments of the Shoup & Oliver feed principle where a crank oscillates back and forth between fixed limits, that is, where an oscillatory crank is employed, in which case means were previously provided for automatically releasing the starter pawl at a definite point

in the cycle of operations of the oscillatory crank.

The need for this manual operation, which, as pointed out was heretofore necessary, is avoided by the present invention by providing automatic means for initiating the feeding operation which requires no attention on the part of the operator.

This is accomplished, in the form of the invention shown in Figs. 1 to 5, inclusive, by normally biasing the starter shaft 31 so that the tripping lever 34 thereon will normally tend to release the pawl 30 from the starting roller 25 and providing means operable during the continued or sustained rotation of the feed shaft 17 for preventing the pawl 30 from being tripped so long as the rotation of the shaft 17 continues, but allowing the starter pawl 30 to be tripped or set to be tripped upon cessation of movement of the feeding shaft 17 or its handle 37.

The specific means for accomplishing this, as shown in Figs. 1 to 5, comprises a cylinder 38 mounted on the frame of the machine, for instance by screws 39, see Fig. 2, and comprising two chambers 40 and 41 divided by a wall 42. The chamber 40 contains a piston 43 having at the end of a rod 44 a head 45 adapted to be held in engagement with a cam 46 on the feed shaft 17 by a spring 47 between the wall 42 and the piston 43. The continued rotation of the feed shaft 17 will thus cause the piston to reciprocate within the cylinder. There is an intake valve 48 in the piston 43 and an outlet valve 49 in the wall 42 so that air will be pumped by the piston 43 into the chamber 41 of the cylinder as the shaft 17 rotates.

The air inlet valve 48 may be of any desired and known type adapted to allow air to enter the cylinder 40 as the piston 43 moves outwardly and to prevent escape of air therethrough when the piston moves inwardly. Such a valve is shown in Fig. 8 as exemplary of the kind of valve which may be used. In the figure, the valve 48 which is an ordinary check valve has a sleeve 70 in which there is located a ball 71 normally urged by a spring 72 against a spun-over seat 73 at the end of the sleeve. The ball is smaller than the internal diameter of the sleeve and hence, when the piston 43 moves outwardly of the cylinder, a partial vacuum is created within the cylinder, causing atmospheric pressure on the ball 71 to move the ball inwardly away from its seat 73 against the tension of the spring 72, thus allowing air to pass the ball and enter the cylinder. Then at the end of the outward stroke (the air intake stroke) of the piston 43, the spring 74 forces the ball 71 against the seat 73 and thus prevents the escape of the air through the valve 48 on the inward stroke of the piston 43.

In the cylinder 41 is a piston 50 normally urged toward the wall 42 by a spring 51 and

connected by a link 52 and lever 53 pivoted at 54 on a bracket 55 and having its other end connected by a link 56 to an arm 57 clamped or otherwise secured on the starter shaft 31. The spring tends to move the piston and this link and leverage system so as to rock the shaft 31 from the position shown in Fig. 3, in which the lateral ear 35 on the trip lever 34 permits the pawl 30 to engage the starter roller, to the position shown in Fig. 4, where the trip lever 34 through its ear 35 has depressed the pawl 30 and released it from the starting roller.

In this form of the invention, before the operation of the feeding mechanism, the parts are in the positions shown in Fig. 4, for air which was contained in the chamber 41 was allowed to pass out through a bleed opening 58. As soon as the feed mechanism starts to operate, the piston 43 is reciprocated by the cam 46 and begins to pump air through the valve 49 in the wall 42 into the chamber 41 and this air forces the piston 50 backwardly against the tension of the spring 51, thus moving the link 52, lever 53, link 56 and starter shaft 31 to a position see Figure 3 where the lateral ear 35 on the trip lever 34 is free of the pawl 30 and allows the latter to rise under the influence of its spring 33 to engage the approaching shoulder 32 on the starting roller 25.

This operation of pumping air into the chamber 41 continues intermittently during rotation of the feeding shaft 17 and is sufficient to keep the piston 50 near the end of its movement, even though, during the intake stroke of the piston 43, air in the chamber 41 bleeds out through the opening 49, the opening being so proportioned that even should the crank 37 be operated slowly, sufficient air pressure would be maintained in the chamber 41 to keep the piston 50 near the outer end of its stroke. This is also controlled by the relative capacities of the chambers 40 and 41 and the strokes of the pistons, any surplus air in the chamber 41 being allowed to escape through an opening 59 in the cylinder which is opened by the piston 50 when the latter is in its rearmost position.

It will be noted that during the operation of the feeding means the piston 50 is allowed, in the form of the invention herein shown, to oscillate slightly near the end of its rearward movement. This, however, has no effect on the starter pawl 30 because sufficient clearance indicated in Fig. 3 is left between the tripping ear 35 on the trip lever 34 and the surfaces 60 on the pawl 20 which it engages to prevent the pawl from being operated, and the starting roller is held with its cutaway portion 26 in the line of contact of the pressure roller during continuation of the feeding operation.

However, when the form has been fed out of the machine and the operator discontinues

rotating the crank 37 and feed shaft 17, the pumping action of the piston 43 ceases and the air in the chamber 41 is allowed to gradually escape through the bleed opening 49 so that soon after cessation of movement of the feed shaft 17, the spring 51 will have caused the piston to reach the limit of its movement inwardly, and in approaching this position the link and leverage system including the link 52, lever 53, and link 56 causes the shaft 31 to be rocked causing the leg 35 and the arm 34 to release the pawl 30 from the starter roller—this operation beginning when the piston reaches the position shown in Fig. 1 and being concluded when it reaches the position shown in Fig. 4.

The pawl will then jump ahead to the position shown in Fig. 4, where it will remain inoperative until at least one half a revolution of the starting roller takes place as above pointed out.

The interval of time which may elapse between the cessation of operation of the feeding mechanism and the release of the starter 25 may be varied from a fraction of a second to a minute or longer, depending upon the size of the bleed opening 49 and any leakage which may occur between the cylinder and piston.

It is preferable, however, that the period be several seconds so that even if the crank 37 should be hesitatingly operated or the handle thereon should inadvertently slip from the operator's grasp for a fraction of a second, the starter would not be tripped.

Of course, the valves 48 and 49 are one way valves and may simply be leathered flaps, if desired.

As stated above, within the scope of this 40 invention, the starter may be tripped subsequently to the last operation of the feeding means as just described, or it may be tripped at the very beginning of the next operation of the feeding mechanism. To do 45 this, the mechanism disclosed in Figs. 1 to 5, inclusive, may be modified as shown in Fig. 6.

In this form of the invention, the starter pawl 30 is in engagement with the shoulder 32 on the starter wheel during the interim between feeding operations. However, as soon as the feeding shaft 17 starts to operate, the cam 46 operates the piston 43 which pumps air into the chamber 41 forcing the piston 50 outwardly against the tension of its spring just as it does in the form shown in Figs. 1 to 5. However, in the form of the invention shown in Fig. 6, the outward movement of the piston causes the starter shaft 31 to be rocked so as to trip the pawl 30 and release it from the starter roller. This is done by connecting a lever 53a which is pivoted at 54a to the piston 50 by the link 52 and pivoting on the lever between its ends a link 56a which has a hook 61 adapted to

engage a pin 62 carried by an arm 63 on the starter shaft 31. The arrangement is such that movement of the link 56a to the right, as viewed in Fig. 6, will trip the starter. The continued movement of the piston 50 and link 56a will cause a cam surface 64 on the link to engage an abutment 65 and cause the link to rise against the tension of a spring 66 so that the pin 62 is no longer engaged by the hook 61. This allows the starter shaft 70 to return to its normal position, and the starter pawl to engage the next approaching shoulder 32 on the starter roller 25.

The continued operation of the feeding mechanism causes the piston 50 to oscillate 80 between the position shown in Fig. 6 and its outermost position, and when the operation of the feeding mechanism ceases the air contained in the chamber 41 is permitted to bleed out through the opening 49 and return the 85 link 56a so that the hook 61 thereon rides up over the pin 62 and drops down behind it ready to rock the shaft 31 upon the next operation of the feeding means.

As above stated, the present invention also 90 embraces in its broader aspects, the provision of automatic means for permitting the feeding operation of the strip or strips to be begun in a machine having a stop for the crank, without necessitating any manual operation to release the stop.

One embodiment of the present invention which accomplishes this result is illustrated in Fig. 7, in which the cam 46, cylinder 38, and pistons 43 and 50 and related parts are 100 the same as in the other figures. In this form, the feeding rollers 16b may have a fixed relation to the length of form to be fed, or they may be narrow annuli operating on the principle disclosed in the patent to 105 Hagemann, #1,456,773. In any event, they are so proportioned or geared to the crank 37b that for one revolution of the crank a set of forms is fed across the platen of the machine.

Heretofore, stop means comprising cooperating parts on the crank 37b and the side 110 10b of the frame were provided to limit the rotation of the crank to one revolution and a manual operation had to be performed to 115 permit the stops to pass each other.

According to the disclosed embodiment of this invention, these cooperating stops are still employed and are constituted by a stop 67 on the side 10b of the machine and a co-operating stop 68 or other portion of the crank 37b constituting a stop. In the specific embodiment shown, the stop 67 is pivoted at 69 on a bracket 70 fastened to the side of the frame 10b and has an arm 71 120 connected by a link 72 to the piston 50.

The device of the present invention, as shown in Figs. 1 to 6, inclusive, is further modified in this form so as to obtain intermittent and repeated operation of the piston 130

43 for each revolution of the feeding shaft 17b by mounting the cam 46 on a stud shaft 73 having a gear 74 meshing with a larger gear 75 on the feeding shaft 17b.

- 5 Still referring to the form of the invention shown in Fig. 7, when the operator desires to feed out a set of forms, the stop 67 is in the position shown in dotted lines in Fig. 7, due to the location of the piston 50 in its innermost position also indicated in dotted lines. As soon as the feed shaft 17 begins to rotate, the cam 46 is rotated through the gearing 74-75 and the piston 43 begins to pump air into the chamber 41 with the result that the piston 50 is forced outwardly against the tension of its spring 51 and the stop 67 is moved to the full line position shown in Fig. 7, where it will be in position to be engaged by the stop 68 on the crank 20 when the latter reaches the position in which it is to be stopped, indicated in dot-and-dash lines.

The operator then tears off the issued forms and, before he is ready to issue another set 25 of forms, the air in the chamber 41 bleeds out through the opening 49 and the stop 67 is moved to the inoperative position shown in dotted lines, ready to permit the next set of forms to be fed by the mere act of turning 30 the crank 37b.

Other variations and modifications may be made within the scope of this invention and portions of the improvements may be used without others.

35 Having thus described the invention, what is claimed as new and for which it is desired to obtain Letters-Patent, is:—
 1. In a manifolding machine having a platen over which a strip is advanced; feeding means for advancing the strip a predetermined length, including means for rendering the feeding means temporarily inoperative to continue to advance the strip after the strip has advanced said predetermined length; and means automatically made operative as an incident to cessation of movement of the feeding means for causing the feeding means to again become operative for strip advancement when it is next desired to advance the strip a predetermined length.

40 2. In a manifolding machine having a platen over which a strip is advanced; feeding means for advancing the strip a predetermined length, including means for rendering the feeding means temporarily inoperative to continue to advance the strip after the strip has advanced said predetermined length; and means restrained from operation during a concluding portion of the operation 45 of the feeding means and automatically made operative upon cessation of movement of the feeding means for causing the feeding means to again become operative for strip advancement upon the next operation of the feeding means.

3. In a manifolding machine having a platen over which a strip is advanced; feeding means for advancing the strip predetermined lengths, including means for rendering the feeding means temporarily inoperative to continue to advance the strip after the strip has advanced said predetermined length; and means automatically made operative upon cessation of movement of the feeding means and requiring a predetermined time for its operation for causing the feeding means to again become operative for strip advancement after the expiration of some time.

4. In a manifolding machine having a platen over which a strip having apertures therein is advanced; feeding means for advancing the strip comprising means which upon engaging the apertures in the strip renders the advancing means inoperative to continue the advancement; strip starting means for again making the feeding means operative for strip advancement; and means restrained from operation during a concluding portion of the operation of the feeding means and automatically made operative upon cessation of movement of the feeding means for conditioning said strip starting means for operations upon the next operation of the feeding means.

5. In a manifolding machine having a platen over which a strip having apertures therein is advanced; feeding means for advancing the strip comprising means which upon engaging the apertures in the strip renders the advancing means inoperative to continue the advancement; a starting roller normally out of engagement with the strip; a trip device for restraining the starting roller from moving into engagement with the strip; and means restrained from operation during a concluding portion of the operation of the feeding means and automatically made operative upon cessation of movement of the feeding means for operating said trip device to cause the latter to move to the position to release the starting roller for movement into engagement with the strip upon the next operation of the feeding means.

6. In a manifolding machine having a platen over which a strip having apertures therein is advanced; feeding means for advancing the strip comprising means which upon engaging the apertures in the strip renders the advancing means inoperative to continue the advancement; starting mechanism for causing the feeding means to again become operative to advance the strips; and means automatically controlled by the sustained operation of the feeding mechanism for maintaining the starting mechanism inoperative during a concluding portion of the operation of the feeding means.

7. In a manifolding machine having a platen over which a strip having apertures

- therein is advanced; feeding means for advancing the strip comprising means which upon engaging the apertures in the strip renders the advancing means inoperative to continue the advancement; starting mechanism normally biased to become operative to render the feeding mechanism again operative to advance the strip; and means for restraining the operation of said normally biased starting means during the sustained operation of the feeding means and automatically operative to release the starting means for operation after cessation of movement of the feeding means.
15. 8. In a manifolding machine having a platen over which a strip having apertures therein is advanced; feeding means for advancing the strip comprising means which upon engaging the apertures in the strip renders the advancing means inoperative to continue the advancement; starting mechanism normally biased to become operative to render the feeding mechanism again operative to advance the strip; and time-controlled means restraining the operation of the normally biased starting mechanism until after cessation of movement of the feeding means.
30. 9. In a manifolding machine having a platen over which a strip having apertures therein is advanced; feeding means for advancing the strip comprising means which upon engaging the apertures in the strip renders the advancing means inoperative to continue the advancement; starting mechanism including a shaft, the operation of which makes the starting mechanism operative to advance the strip; and means for operating said starting shaft automatically after the expiration of some time following cessation of movement of the feeding means.
35. 10. In a manifolding machine having a platen over which a strip having apertures therein is advanced; feeding means for advancing the strip comprising means which upon engaging the apertures in the strip renders the advancing means inoperative to continue the advancement; starting mechanism adapted to cause the feeding mechanism 40 to again become operative to advance the strip; means tending to cause the starting means to be operative; and a slow motion device restraining the last-named means against operation during a concluding portion of the 45 operation of the feeding means and releasing of said means for operation after cessation of movement of the feeding means.
50. 11. In a manifolding machine having a platen over which a strip having apertures 55 therein is advanced; feeding means for advancing the strip comprising means which upon engaging the apertures in the strip renders the advancing means inoperative to continue the advancement; starting means for causing the feeding means to again become 60 effective to advance the strip and including a strip device for controlling the operativeness and inoperativeness of the starting mechanism; and a pneumatic device operated by the feeding means for controlling said trip device.
12. In a manifolding machine having a platen over which a strip having apertures 65 therein is advanced; feeding means for advancing the strip comprising means which upon engaging the apertures in the strip renders the advancing means inoperative to continue the advancement; starting means for causing the feeding means to again become effective to advance the strip and including a trip device for controlling the operativeness and inoperativeness of the starting mechanism; and an automatic time-controlled device operated by the feeding means for controlling the operation of said trip device.
75. 13. In a manifolding machine having a platen over which a strip having apertures 80 therein is advanced; feeding means for advancing the strip comprising means which upon engaging the apertures in the strip renders the advancing means inoperative to continue the advancement; starting means for causing the feeding means to again become effective to advance the strip and including a trip device for controlling the operativeness and inoperativeness of the starting mechanism; and a pneumatic device connected to the trip device for controlling the operation of the latter; and an air pump 85 operated by the feeding means for supplying air to said pneumatic device.
90. 14. In a manifolding machine having a platen over which a strip is advanced; feeding means for advancing the strip predetermined lengths, including means for rendering the feeding means temporarily inoperative to continue to advance the strip after the strip has advanced said predetermined length; means for causing the feeding means 95 to again become operative for strip advancement including a trip device; and a pneumatic device operated by the feeding means 100 for controlling said trip device.
105. 15. In a manifolding machine having a platen over which a strip is advanced; feeding means for advancing the strip predetermined lengths, including means for rendering the feeding means temporarily inoperative 110 to continue to advance the strip after the strip has advanced said predetermined length; means for causing the feeding means to again become operative for strip advancement including a trip device; and an automatic time-controlled device operated by the 115 feeding means for controlling the operation of said trip device.
120. 16. In a manifolding machine having a platen over which a strip is advanced; feeding means for advancing the strip predetermined lengths, including means for rendering the feeding means temporarily inoperative to continue to advance the strip after the strip has advanced said predetermined length; means for causing the feeding means to again become operative for strip advancement including a trip device; and an automatic time-controlled device operated by the 125 feeding means for controlling the operation of said trip device.
125. 17. In a manifolding machine having a platen over which a strip is advanced; feeding means for advancing the strip predetermined lengths, including means for rendering the feeding means temporarily inoperative to continue to advance the strip after the strip has advanced said predetermined length; means for causing the feeding means to again become operative for strip advancement including a trip device; and an automatic time-controlled device operated by the 130 feeding means for controlling the operation of said trip device.

mined lengths, including means for rendering the feeding means temporarily inoperative to continue to advance the strip after the strip has advanced said predetermined length; means for causing the feeding means to again become operative for strip advancement including a trip device; a pneumatic device connected to the trip device for controlling the operation of the latter; and an air pump operated by the feeding means for supplying air to said pneumatic device.

Signed at Bridgeport, in the county of Fairfield, and State of Connecticut, this 21st day of December, 1929.
